UNITED STATES PATENT OFFICE

2,546,621

PAPER CUP MAKING MACHINE

Paul E. Wixon and Clarence E. Chapman, Baltimore, Md., assignors to Joseph Shapiro

Application January 6, 1948, Serial No. 748

8 Claims. (Cl. 93—39.3)

1

In general our invention seeks to improve the several units of a machine of the type disclosed in Letters Patent No. 1,766,420 issued June 24, 1930.

A machine of this type comprises several units, namely, two paper roll supporting units, body and bottom blanking die units, three revolving turrets to one of which the cup-body blanks are delivered and by which the body blanks are first conveyed past a glue-applying unit and then delivered to a second one of the turrets which carries forming mandrels to which the blanks are applied by mechanism and to which mandrels bottom blanks are first applied. The second turret carries the assembled body and bottom portion to a device for curling the bottom edge of the body blank inwardly and then conveys the finished cup to a discharge station for delivery from the machine.

Our invention has for its specific objects:

1. To improve the paper feed mechanism that conveys the paper to the body blanking dies.
2. To improve the construction of the body blanking die mechanism.
3. To improve the construction of the blank conveyor turret unit.
4. To improve the construction of the bottom blanking and forming mechanism and the forming turret unit.
5. To provide a new locking mechanism for the forming turret.
6. To provide a new and improved bottom expander.
7. To provide an improved bottom ejector and curl unit.
8. To improve the top-ending turret unit.
9. To improve the power transmitting system to all moving parts and provide for adequate lubrication.
10. To provide an improved cup-beading unit.
11. To provide a more efficient machine which will more effectively serve its intended purpose than the machine of Patent No. 1,766,420 aforesaid.

Other objects will in part be obvious and in part be pointed out hereinafter.

To the attainment of the aforesaid objects and ends invention resides in the novel features of construction, combination and arrangement of parts, all of which will be first described in detail and then be specifically pointed out in the appended claims, reference being had to the accompanying drawings in which:

Figs. 1 and 1^A when joined on the lines 1—1^A constitute a top plan view of the machine, parts being shown in section and parts being omitted.

2

Fig. 2 is a horizontal section taken in part just above the flange 2 and in part just below the top of the base section 1.

Fig. 3 is a top plan view of the feed and drive assembly and the punch die assembly for feeding and cutting the cup body blanks.

Figs. 4 and 4^A when joined on the lines 4—4^A constitute a side elevation of the parts shown in Fig. 3.

10 Fig. 5 is a detail vertical section on the line 5—5 of Fig. 3.

Fig. 6 is a side elevation on a larger scale of one of the perforator feed finger inserts.

Fig. 7 is a side elevation of the same looking from right to left in Fig. 6.

Fig. 8 is a bottom plan view of the same.

Fig. 9 is a detail plan view, on a smaller scale than Fig. 3, of the punch plate.

Fig. 10 is a section on the line 10—10 of Fig. 9.

Fig. 11 is a top plan view of the blanking die.

Fig. 12 is a rear elevation of the same.

Fig. 13 is a detail cross section on the line 13—13 of Fig. 2.

Fig. 14 is a detail top plan view of the blank picker head.

Fig. 15 is an enlarged section on the line 15—15 of Fig. 14.

Fig. 16 is a detail longitudinal section on the line 16—16 of Fig. 1.

30 Fig. 17 is a section on the line 17—17 of Fig. 16.

Fig. 18 is a detail top plan view on a larger scale of one of the blank locating stops.

Fig. 19 is a side elevation of the same.

Fig. 20 is an enlarged plan view of one of the blank clamp fingers and tip.

Fig. 21 is a side elevation of the same.

Fig. 22 is a detail cross section on the line 22—22 of Fig. 2.

Figs. 23 to 27, inclusive, when Figs. 23, 24 and 40 25 are joined together on the vertical lines A—B and C—D, respectively, and when these three figures are joined to Figs. 26 and 27 on the horizontal lines E—C—F and Figs. 26 and 27 are joined on the vertical line C—D, constitute a cross section on the lines 23—27 of Fig. 1.

45 Fig. 28 is a detail side elevational view showing the roll throwout means and the bottom paper feed.

Fig. 29 is a detail side elevation of the lower bottom paper unwinder.

50 Fig. 30 is a continuation of Fig. 29, the two figures reading as one upon joining the line A—B in those figures.

Fig. 31 is a longitudinal section of the same taken on about the line 23—27 of Fig. 1.

3

Fig. 32 is a cross section on the line 32—32 of Fig. 16.

Fig. 33 is a side elevation of the two hinged parts of the folder separated.

Fig. 34 is a detailed side elevation of the blank clamp.

Fig. 35 is an end elevation of the same showing its connection to the folder blank clamp operating shaft.

Fig. 36 is a top plan view showing the bottom ejector and curl mechanism.

Fig. 37 is a vertical section on the line 37—37 of Fig. 36.

Fig. 38 is a continuation of Fig. 37 and may be read with that figure as one upon joining the lines A—B in those figures.

Fig. 39 is a detail horizontal section on the line 39—39 of Fig. 37.

Fig. 40 is an elevation of the bottom curl roller head.

Fig. 41 is a section on the line 41—41 of Fig. 40.

Fig. 42 is an elevation of one of the bottom curl rollers.

Fig. 43 is a top plan view of the bottom expander.

Fig. 44 is a central vertical longitudinal section of the same on the line 44—44 of Fig. 43.

Fig. 44^A is a detail elevation of a portion of the lever 433.

Fig. 45 is a continuation of Fig. 44 and when joined with that figure on the lines A—B, those figures may be read as one.

Fig. 46 is a face view of the cam shown in part in Fig. 45.

Fig. 47 is a cross section on the line 47—47 of Fig. 46.

Fig. 48 is an enlarged side elevation of the bottom expander roller.

Fig. 49 is an elevation of the same looking from right to left of Fig. 48.

Fig. 50 is an end elevation of the bottom expander slide block shown in Fig. 44.

Fig. 51 is a detail view of the same looking from right to left in Fig. 50.

Fig. 52 is a detail plan view of the bottom expander roller operating slide block shown in Fig. 44.

Fig. 53 is a side elevation of the same.

Fig. 54 is a rear elevation of the same.

Fig. 55 is a top plan view of the top ending turret and the top curl and beader devices.

Fig. 56 is a cross section on the line 56—56 of Fig. 55.

Fig. 57 is a detail section on the line 57—57 of Fig. 56.

Fig. 58 is an enlarged detail vertical section of a portion of the top ending cone insert.

Fig. 59 is a view partly in vertical section and partly in elevation looking in the direction of the two headed arrow *a* in Fig. 55.

Fig. 60 is a detail vertical section on the line 60—60 of Fig. 55.

Fig. 61 is a detail end elevation along the line 61—61 of Fig. 60.

Fig. 62 is an enlarged detail section on the line 62—62 of Fig. 60.

Fig. 63 is a detail plan view of the top curl clamp.

Fig. 64 is an enlarged detail section on the line 64—64 of Fig. 55.

Fig. 65 is an inverted plan view of the segmental header.

Fig. 66 is a top plan of the gluing mechanism and the blanking press and gluing table top.

Fig. 67 is a side elevation of the same.

4

Fig. 68 is a cross section on the line 68—68 of Fig. 66.

Fig. 69 is a detail section on the line 69—69 of Fig. 66.

Fig. 70 is a detail section on the line 70—70 of Fig. 66.

Fig. 71 is a detail front elevation of the bottom forming punch.

Fig. 72 is a part side elevation and a part central section of the same, parts being broken away.

Fig. 73 is a section and part elevation on the line 73—73 of Fig. 1A.

Fig. 74 is a detail elevation of the blow-off air connection bracket.

Fig. 75 is a top plan view of the same.

Fig. 76 is a plan view of the air connection pad.

Fig. 77 is a detail side elevation of the cup blow-off chute and one top ending cup.

Fig. 78 is a schematic view showing the lubricating system employed in the machine.

In the accompanying drawings in which like numerals and letters of reference indicate like parts in all the figures, 1 represents the upper half of the base of the machine, and 14 represents the lower half of the same. The two parts of the base have flanges 2 and 15 respectively through the medium of which and bolts or screws 16, the sections of the base are secured together. The upper and lower base halves 1 and 15 may be hingedly connected by means of suitable hinge elements secured to pads on the base parts as will hereinafter more fully appear.

Inspection openings 3 with covers 4 are provided and the upper base section is also provided with a number of openings 5 to 13 inclusive for purposes later to appear. Likewise the lower base section has openings 17 to 20 inclusive for purposes later to appear.

By referring now to Fig. 2, it will be seen that two parallelly disposed cam shafts 21 and 27 are mounted in the upper base section 1, the shaft 21 being hereinafter referred to as the front cam shaft while the shaft 27 will be referred to as the rear or back cam shaft.

Secured to the base and closing opening 6 is a front cam shaft bearing housing 22, containing a packing housing 23 and cover 24. The front cam shaft is also supported by bearing hangers 25, 26. The back cam shaft 27 is journaled in bearing hangers 28 and 29.

Journaled in a bearing 34, 35, 36 (forming a closure for opening 5) and a bearing hanger 33 is a power shaft 30 which is geared to the cam shafts by bevel gears 31, 31 and 32, 32 respectively. The shaft 30 is driven from an electric motor 39 which, by belt and pulley connection 40, drives a speed reducer 38 secured to a mounting base 37 mounted on the rear of the base.

Secured to a collar 42 on the shaft 21 is a blanking cam 41. Adjacent the cam 41 on shaft 21 is a press lever operating fork slide block 43 and collar 44. 45 designates a fork which operates on the slide block 43. The fork 45 carries a roller 46 to run in the groove 41^a of the cam 41. The lower half 47 of a press lever operating rod is screwed into the fork 45 and passes through a bushing 48 that projects through and serves as a plug for the hole 7 in the base 1. The rod 47 carries a dust cap 49 to fit over the upper end of the bushing 48 (see Fig. 4). The lower section or half of the press lever operating rod 47 is coupled at 50, to the upper section 51 by an adjustable coupling nut 50 and the upper end of rod section 51 has a clevis 52 that is pinned at 54 to a press

lever 53. As best shown in Fig. 3, the press lever 53 is pivoted on a pin 65 that is carried by a bracket 64 mounted on the top of the base section 1.

A punch plate 56 is slidably mounted, for up and down movement, on guide pins 121 mounted on the base and passing through punch plate guides 57. The plate 56 also has an apertured lug 58 for a link pin 59 to the ends of which a forked link 55 is pivoted, the link 55 being also pivoted on a pin 59^a carried by the lever 53.

A blanking punch 60 is secured to the underside of the plate 56 by screws 66 while a blanking punch stripper plate 61 is yieldably suspended by guide pins 62 and springs 63 from and below the plate 56 (see Fig. 4).

As best shown in Figs. 4 and 13, a die holding stand 61 is secured to the base section 1, to one face of which the bottom half 68 of a waste paper cutter is secured, the top half 69 being mounted on the plate 56, spacers 70 being provided so as properly to line up the cutting blades 68 and 69 (Fig. 4).

Mounted on the end of the base where the cup body blanking mechanism is located is the paper perforator feed and drive assembly. By reference to Figs. 3 and 4 it will be observed that 71 represents perforator feed brackets on which are mounted feed plate holding bar spacers 72 which carry a feed plate holding cross bar 73 to which and to an angle bracket 74 a feed plate 75 is attached in any suitable way. The plate 75 has longitudinal grooves 75^a with which perforator feed fingers 80 cooperate. Paper guide bars 76 are mounted on plate 75 according to the width of paper used.

A perforator feed finger operating shaft 77 is journaled in the brackets 71 and carries pivot screws 91 between which a perforator feed finger pivot rod 79 is mounted. Springs 92 on the rod are anchored to the levers 78 and to collars 79^a and continuously tend to hold the fingers 84 with their inserts 80 in the grooves 75^a. The inserts 80 (see Figs. 6, 7 and 8) have flat heads 81 which ride on the plate 75 and chisel points or teeth 82 which ride in the slots or grooves 75^a. One of the perforator feed fingers 84 has a lifting roller 83 which cooperates with a perforator feed finger lifting cam 85 (see Figs. 3 and 4) which cam is fulcrumed on a stud 87 carried by a bracket 86 that is mounted on the plate 75. A spring 88 is anchored to a bracket 89 and to a stud 89 on the cam 85 to hold its end 85^a yieldably down on the adjacent guide bar 76. The cam 85 is so located above the bar 76 that on the forward movement of the fingers 84 the roller 83 will ride under the cam and on the return movement the roller 83 will ride up and over the cam, as will more fully appear later.

The backward movement of the levers 78 is arrested by means of adjustable stops 94 on brackets 97 carried by the perforator feed brackets 71 and the levers 78 are constantly urged toward such stops by a coil spring 96, one end of which is connected to a hook 97 and the other end is connected to an arm 95 secured on the shaft 77. Also secured on the shaft 77 is a cam roller lever 98 which carries a cam roller 99 (Fig. 3) that is engaged by a cam 102 which is rotatable on a stud 101 and is operatively connected to a gear 103 also journaled on the stud 101. The roller 99 is journaled on a stud 100 that is carried by the lever 98.

The gear 103 meshes with a cam drive gear 104 that is mounted on a drive shaft 105. The

shaft 105 is journaled in suitable bearings in the brackets 71 (Fig. 5). The shaft 107 is journaled in eccentric bushings 108 that are oscillatably journaled in the brackets 71 and capable of being rocked by arms 110 secured to the bushings and connected together by a rod 111.

Mounted on the shaft 105 is a paper unwinder drive roll 106 while a paper unwinder driven roll 109 is carried by the shaft 107.

Secured to the shaft 105 is a bevel gear 112 which meshes with a pinion 115 (Fig. 4, 4^A) on a vertical drive shaft 114 that is journaled in bearing brackets 113 secured to the base part 1. The shaft 114 is driven from the front cam shaft 21 through bevel gears 116 and 117.

The paper for the body of the cup is in a roll 607 held between plates 608 on a shaft 609 resting on bearing rollers 610 in frames or brackets 611 and held in place by centering screws 612 (Fig. 1). The paper is placed over the roll 106 and around the roll 109 and from thence is carried in a loose loop over the free edge of the plate 75, and along the plate between the guide bars 76, under the feed fingers 84 by which fingers the paper is advanced to the body blanking mechanism.

It will be understood that when the paper is passed under the fingers 84 their teeth 82 will perforate the paper and thereby effect a positive connection with the paper so that as the shaft 79 is advanced from its back position where levers 78 rest against the stops 94, to the position shown in Figs. 3 and 4 the paper will be advanced a predetermined distance with its advance end between the body blanking dies.

While the dies are in operation shaft 79 is quickly returned to its back position, roller 83 riding over the cam 85 to free the teeth 82 from the paper and drop the teeth again into the paper after the fingers shall have been lifted and cleared the cam 85. The paper is thus fed to the blanking dies step-by-step.

The blanking die 118 with which the blanking punch 60 cooperates, is mounted on the die holding stand 61. A waste paper guide plate 119 encircles the upper end of the die 118 and is mounted on spacers 120. The waste paper is advanced between the cutting blades 68, 69 after each blanking operation.

The blank picker

Referring now more particularly to Figs. 11 to 15 inclusive it will be seen that 122 indicates a picker shaft guide which is mounted on the base part 1 and projects through the hole 8. Mounted for up and down movement in the guide 122 is a hollow picker shaft 123 which carries a hollow blank picker head 124 that operates in the blanking die 118.

The head 124 is of triangular form in plan view (Fig. 14) and is provided with three rubber suction cups 129 held to the head 124 by screws 130 which have bores 130^a to effect communication between the cups 129 and the interior air chamber 127 of the head 124 (Fig. 15). 128 is a spacer for the cup 129.

The head 124 is also provided with pilot rods 125 which work up and down in bearings 126 in the guide 122 (Fig. 13). A suction or vacuum hose 131 is connected to the lower end of the shaft 123, and functions in a manner later to be explained.

Fulcrumed on a stud 133 carried by a bracket 132 that is secured to a side wall of the base 75 section 1, is a picker cam lever 134 that has a

cam roller 135 to cooperate with a picker cam 136 secured to a hub 137 that is fast on the cam shaft 21.

Mounted slidably on the shaft 123 is a trunnion 138 with which a trunnion block 139 in the fork of lever 134 cooperates. The shaft 123 has a nut 141 and a safety spring 140 that engages the block 138.

142 is the blanking press table top which has a passage 142^a (Fig. 66) for the picker. The table top 142 is supported on suitable supports 143.

The picker shaft guide 122 has a bracket 144 (Fig. 16) in which is journaled a shaft 145 on which is mounted a yoke 147 having an adjustable finger 148. Operating arms 146 are also mounted on the shaft 145.

Pivoted on studs 149 on the arms 146 are blank clamp finger operating rods 150. These rods pass between guide lugs 151 on each side of the picker shaft guide 122 and through bearings 157 on the sides of the blank conveyor turret shaft housing 154.

Blank conveyor lifting rod springs 152 on rods 150 lie against washers 152^a that abut the lugs 151 and adjustable collars 153 secured to the rods 150 by set screws 153^a.

The housing 154 projects down through the hole 9 in the base section 1. Journaled in ball bearings 155, held in place by bearing caps 156, is the conveyor turret shaft 165 on which a turret wheel 164 is mounted to turn with the shaft 165.

Projecting from the housing 154 are lugs 158 between which, on a fulcrum stud 159 a blank clamp lifting arm 163 is mounted. The lifting arm 163 carries adjustable blank clamp finger lifting rod bumper screws 160 whose heads engage the ends of the rods 150. The arm 163 has a blank clamp finger lifting shoe 161 and a bottom shoe 162.

The turret wheel 164 is provided with a set (six as shown) of brackets 166 each having a pair of adjustable blank locating stops 167, a shaft 168 journaled in bearings 166^a and carrying a pair of blank clamp fingers 169 (having tips 182) and springs 181 for continuously urging said fingers into their blank clamping position. Also secured to the shaft 168 is a lifting shoe 170 (Figs. 16 and 17). Beneath each shoe 170, vertically slidably mounted in a suitable bearing 164^a, is a headed blank clamping lifting pin 171. The pins 171 alternately are engaged by the adjustable finger 148 and the top shoe 161 to lift the pins, as will more clearly appear later.

172 is the blank conveyor Geneva cam bracket (Figs. 16 and 22) in which is journaled the blank conveyor Geneva cam shaft 178 on which is mounted a Geneva cam 173 and a Geneva cam roller 174. The Geneva cam 173 and roller 174 cooperate with a Geneva gear 175 on the shaft 165. The shaft 178 also carries a gear 176 with which meshes a driving gear 177 on the back cam shaft 27 (Fig. 22).

The turret wheel 164 has a pair of clamp finger pads 179 for each clamp unit and these pads are grooved at 189 to receive the bent over ends 167^a of the blank locating stops 167.

The blank conveyor unit is of a well known construction and no claim is made to it per se in this application.

Referring now to Figs. 23 to 27 inclusive, it will be seen that 183 indicates the forming turret shaft bracket which is mounted on the top of the base part 1 and projects through the open-

ing 10 therein. The forming turret shaft 187 is journaled in ball bearings 188, 189. A forming turret hub 186 is secured to the shaft 187 while the forming cone carrying turret body 184 is mounted on the hub 186. The body 184 has a chamber 184^b that is closed by a cover 185. In addition to being secured to the hub by cap screws 184^a (Fig. 24) the body 184 and hub 186 are held together on the shaft 187 by a clamping collar 190 and nut 190^a.

Forming cones 191 are secured to the body 184 with their axes radially disposed. The cones 191 are each hollow and each has a recessed end piece 191^a in the recess of which a bottom ejector head 192 operates. The head 192 is detachably carried by an injector spindle 193 which passes through the inner end of the cone 191 and projects into the chamber 184^b where it is engaged by a chambered radially slidably mounted bottom ejector shoe 202 within whose chamber on a stud 204 a roller 203 is mounted.

195 is a coil spring on the spindle 193 the tension of which may be adjusted by means of a collar 194 secured to the spindle by a set screw (Fig. 24). The head 192 and spindle 193 have a bore 196 with a port 197 which, at the proper time, is designed to register with port 199 (in a bushing 198) that communicates with an air duct 200 in the turret body 184. A guide pin 201 is provided for the spindle 193. Slidably up and down in bearings 216 on the turret body 184 are bottom ejector lifting rods 205. The rods 205 have a pin and slot connection 215 with the bearings 216. The upper ends of the rods 205 have beveled portions 205^a which cooperate with the rollers 203 so that when the rods 205 are raised the shoes 202 will be slid radially outwardly to push the spindles 193 outwardly and eject the bottoms that are in the recessed pieces 191^a. The rods 205 have rollers 206 at their lower ends for engaging cam tracks 207 which are mounted on the bracket 183.

Mounted on the cover 185 are seam clamp lever fulcrum brackets 208, one to each cone 181.

Pivoted at 209 to each bracket 208 is a seam clamp lever 210 which carries a seam clamp 211 faced with a rubber block 212. When a body blank has been folded about the forming cone 181 as will later more fully appear, the lapped portions will lie beneath the block 212 so that when lever 210 is moved down, block 212 will press the lapped portions (to one of which glue was previously applied as will be explained later) together to secure the seam. The levers 210 are constantly urged to their clamping position by coil springs 203 suitably anchored to cross bars or plates 210^a and to the turret body 184. The plates 203 are secured to their respective levers 210 by stop screws and nuts 210^a.

Mounted for up and down movement in guide bearings 217 are clamp lifting rods 218 having rollers 219 at their lower ends for engaging a cam track 219 and having their upper ends engaging the stop screws 210^a. A pin and slot connection 214 holds the rods 218 from turning in their bearings.

The turret shaft 187 is provided with a Geneva gear 220 which is driven by a Geneva cam 241 on a shaft 222 that is journaled in bearings 223 carried by a bracket 221 (Figs. 25, 27). The shaft 222 is driven from the back cam shaft 27 through worm gears 224, 225.

226 indicates the forming turret cover while 227 indicates a support for the upper end of the shaft 187.

228 indicates the forming turret locking base on which the shaft support 227 is mounted. Also mounted to slide back and forth along a radius of the turret is a forming turret locking shaft housing. The housing 230 works in a dove-tailed runway 232 on the top of the base 228 as best shown in Fig. 25. The base 228 is hollow and has openings with inspection covers 229 on its sides and top and bottom openings 228^a, 228^b, the latter aligning with an opening 1^a in the base 1.

Within the housing 230 is slidably mounted the forming turret locking head shaft 240 to which a locking head 231 is detachably mounted. The head 231 has a socket 231^a to fit over the adjacent end 191^a of a forming cone 191, the head being cut-away as at 231^b so as to clear the seam clamp 211. A coil spring 240^a continuously urges the shaft and head toward the forming cone, such movement being adjustably arrested by nuts 240^b and washers 240^c. 240^d represents an oil duct in the shaft 240 for bearing lubrication, a suitable fitting 240^e being provided for the usual purpose.

The housing 230 has a projection 233 that passes through the opening 228^a into the base 228 and carries a trunnion block pin 234 that passes through trunnion blocks 235^a carried by the fork of the lever 235. The lever 235 is pivoted on a fulcrum pin 237 carried by a bracket 236 secured to a wall of the base 1. The lever 235 has a cam roller 238 to engage the forming turret locking cam 239 that is mounted on the back cam shaft 27.

When the housing and its contents are moved from right to left in Fig. 25 by lever 235 under the influence of cam 239 and head 231 is placed over the end 191^a of the cone and body blank thereon, the turret is positively locked in position regardless of any wear or play in the turret turning means, so that the bottom blanking and forming means may function properly.

Referring now particularly to Figs. 23, 24, 26, 70 and 71, it will be seen that diametrically opposite the turret locking mechanism, the bottom blanking and forming mechanism is located. A stand 242 for the blanking and forming mechanism is mounted on top of the base 1 and is provided with a bushing 243 in which a punch holder 244 is slidably mounted on an axis radial to the turret and in the plane containing the axes of all the conical formers 191.

Slidably mounted between guides 250 on top of the stand 242 is a waste paper cutter slide 246 which carries the lower one 247 of a pair of cutter blades and is secured to the holder 244 by means of a stud 245 that passes through a slot 248 in the stand 242. The upper waste paper cutter 249 is mounted on the blanking and forming die holder 253 which is mounted on a bracket 251 that is secured to the stand 242. The bottom blanking and forming die 252 is mounted in the holder 253, by a retaining plate 254.

255 is a shaft which passes into a bore 244^a in the holder 244. The shaft has a bore 255^a and counterbore 255^b into which is threaded the bored shank of a bottom forming punch 253 which is clamped to the holder 244 by a ring 244^b.

As will be clear by reference to Figs. 71 and 72, it will be seen that the bottom forming punch 253 has a fluted outer surface 257^a and is bored to receive the valve like insert 257^c, a seat 257^b being provided as shown in Fig. 71. The valve 257^c is connected for limited axial movement with the punch by a pin and slot connection 257^e, 257^d.

Mounted on the shaft 255 between the punch

holder 244 and an adjustable collar 256^a is a safety spring 256, while a trunnion 260 is also adjustably secured to the shaft 255 between collars 260^a. A lever 259 is pivoted on a fulcrum shaft or pin 263 carried by a bracket 262 secured to a wall of the base 1. The lever 259 has its upper end forked to straddle shaft 255 and has trunnion blocks 261 to cooperate with the trunnion 260. The lower end of the lever 259 (Fig. 26) is pivoted to the connecting link 266 of an eccentric strap 264 that engages an eccentric 265 on the front cam shaft 21.

The upper section 283^a of the paper chute 283 passes up in front of the die 252 and has an opening 283^b for the punch 253 to pass through. It also has an opening 283^c into which the paper feed rolls 269 and 270 project. The paper feed roll 269 is mounted on a shaft 272 journalled in a bracket 267 fixed to the stand 242 while the roll 270 is mounted on a shaft 273 that is journalled in a bracket 268. The bracket 268 is pivoted at 271 to a portion of the bracket 267. The bracket 268 has a lug 277 through which a throw-out rod 279 passes. A spring 280 is mounted on the rod 279 between the lug and a washer 281^a and is held under tension by nuts 281. 278 is an eccentric shaft to which the rod 279 and a throw-out lever 282 are secured so that by turning the lever 282 one way the roll 270 will be held in engagement with roll 269 and when turned in the other direction the rolls 269 and 270 will be separated.

The shafts 272 and 273 carry meshing spur gears 272^a and 273^a respectively. On the end of shaft 272 from where the gear 272^a is located, a sprocket 275 is secured. A chain 276 passes over the sprocket 275 and under a sprocket 274 (Fig. 2) on cam shaft 21, to drive the rolls 269, 270. It will be noticed by reference to Fig. 24 that the rolls 269 and 270 are segmental so that during about one half their revolution they do not engage the paper between them. It is while the rolls 269, 270 do not perform their feeding function that the bottom blanking and forming dies operate.

45 With the parts positioned as shown in Fig. 24 paper is being fed up by the rolls 269, 270. As soon as the rolls 269, 270 have completed their function of advancing the paper strip, the blanking punch is advanced and punches out a bottom blank; further forward movement of the holder 244 is arrested by the die 252 but the punch 257 will continue its forward movement to push the blank through the die and into the end of the conical former. In doing this the bottom blank 55 will have its marginal portion bent over at right angles, the reduction in diameter of that portion being taken up in the flutes 257^a. As the punch 257 recedes the formed bottom will remain in the end 191^a of the conical former and 60 be carried around to the station where the body blank is applied as will later be more fully explained.

Referring now to Figs. 2, 29, 30 and 31 it will be seen that 284 designates the bottom paper unwind 65 winder drive roll bracket that projects from a wall of the base 1 and has bearings in which the driven roll shaft 287 of the bottom paper unwinding mechanism is journalled. The driven roll 287 is journalled in a bracket 285 that is pivoted at 285^a in the bracket 284. The roll 287 is held to contact the roll 289 by a spring 291. The bracket 285 has a lock-out pin 288 to be engaged by a latch 289, that is pivoted at 292 to the bracket 284 and is held in contact with the pin 288 by a 70 spring 290 (see Fig. 29).

293 designates a bracket which projects at an angle of 45° to the side of the base and carries a spindle 295 on which a guide roll 294 is journaled.

Mounted in bearings 299 is a shaft 296 which is coupled at 298 to the drive roll pin or stub shaft 297 and which is driven by a pulley and belt drive 301, 302, 303 from cam shaft 21. A spindle bracket 303 is mounted on the base and rotatably carries a spindle 304 having paper roll holding flanges 305 between which the core 306 of the roll of bottom paper is clamped and held by a set screw 307. Paper from the roll 306a passes under roller 294, between rollers 286 and 287 into and through chute 283 between rollers 289 and 270.

The body blank folding mechanism is best shown in Figs. 16 and 32 to 35 inclusive, in which 309 represents the folder shaft guide which is mounted in the base 1 and projects into hole 11. An operating sleeve 309 works up and down in bearings 308a in the bracket 308. The sleeve 309 has a cross slot 310 through which and a slot 326 in the bracket and an opening 324a in a clamp operating shaft 324, a lifting spring anchor bar 327 passes. The shaft 324 rides in bearings 325 in the sleeve 309. The sleeve 309 near its lower end carries a trunnion 312. The trunnion 312 is held in place on the sleeve by means of a nut 312a, a washer 315, safety spring 314 and split nut 313. A forked lever 316 carries trunnion blocks 311 for the trunnion 312 and is pivoted at 318 to a bracket 317 mounted on a wall of the base 1. The lever 316 has a cam roller 322 that works in the groove 319a of a cam 319 that has a hub 320 secured to the front cam shaft 21 (Figs. 2 and 33). The adjacent front cam shaft hanger 25 has a slot 321 to clear the cam roller stud nut 322a. 323 represents the folder operating sleeve head that is secured on the upper end of the sleeve 309 and carries a pair of diametrically oppositely disposed eye bolt trunnion blocks 339, having trunnion pins 339a.

Secured to hooks 329 and to the ends of the bar 327 is a pair of clamp lifting springs 328. Adjustable stops 348 limit the upward movement of bar 327.

Mounted on a hinge pin 331 carried by the upper end of the shaft 324 are folders 330, 330a which are designed to embrace a former 291 when closed on the same. The folders 330, 330a are operated from the head 323 by means of eye bolts 337 that are pivoted at 337a to the respective folders and pass through the trunnion blocks 339. Coil springs 338 are provided on the bolts 337 between the folders and the trunnion blocks and stop and adjusting nuts 338a are threaded on the bolts below the trunnion blocks, thus providing a yielding connection between the folders 330, 330a and the folder operating sleeve 309.

Mounted on the upper end of the shaft 324 by means of a cross pin 333 and slot 335 is a blank clamp 332 for pressing a cup body blank against the under side of a former and holding it in position for the folders to act. The clamp 332 has spring sockets 336 in which and in similar sockets 336a in the end of the shaft 324 blank clamp springs 334 are mounted. Thus the clamp 332 has a limited yielding movement on the shaft 324. When a body blank has been placed in position below the former 291 (Fig. 16) and over the folder, cam 319 will raise lever 316, which, in turn, lifts the sleeve 309, which allows springs 323 to raise bar 327 and consequently shaft 324, until clamp 332 places the blank firmly against the former 291 whereupon folders 330, 330a will

fold the blank around the former, overlapping the edges of the same. The seam clamp lever 210 then comes down to press the overlapped parts tightly together and hold them so until the glue (previously applied as will specifically appear later) has set. Having performed their functions, folders 330, 330a and clamp 332 are then lowered again.

In closing around the former 291 the folders 10 do not meet but sufficient space between their opposite edges is provided for the seam clamp to work.

The clamp lifting roller pins 340 project outwardly from the axis of the forming turret so as to ride the shoe 343 of the seam clamp lever 342 which is pivoted at 342a on a bracket 341 located adjacent the folding mechanism (Fig. 16). 344 designates a trip lever-locking spring and 345 indicates an adjustable stop screw on lever 342. 20 The folder operating sleeve head 323 has adjustable screws 346 and 347, the former cooperating with the bottom shoe 162 of arm 163 and the latter cooperating with the projection 342b of lever 342. With head 323 down (Fig. 16) arm 25 163 is depressed and consequently pins 171 are not engaged nor is lever 342 engaged.

When, however, head 323 is raised arm 163 is released so springs 152 can operate yoke 147 and arm 163 to operate blank clamp lifting pins 171 30 as soon as clamp 332 shall have engaged the paper and pressed it against former 291. As soon as the forming turret has reached the position Fig. 16, roller 218 will just have passed the high part of cam track 219 but it cannot fall 35 due to the pin 340 now resting on shoe 343. After the paper blank shall have been folded around the former, further upward movement of the head 323 causes screw 347 to engage projection 342b and move lever 341 to clear pin 340 whereupon the seam clamp is dropped forceably onto the seam of the paper cup body.

Referring now to Figs. 36 to 42 inclusive it will be seen that Figs. 36 and 37, 38 indicate the position of the parts at the bottom ejector and curl station D (A indicates the bottom blanking and forming station, B the body folding and forming station, C the turret locking station, E the bottom expander station and F the transfer station to the top ending turret, see Figs. 1, 1A).

50 As shown in Fig. 37, 349 represents the bottom curl cam housing and shaft support which is mounted on the base 1 and projects through the hole 12. Journaled in bearings 351 in the support 349 is a cam shaft 350 to the lower end of which is fastened a bevel gear 389 which meshes with a similar gear 389a on the back cam shaft 27. On the upper end of shaft 350 a cam 352 is secured. The cam 352 has a lower cam groove 353 and an upper cam groove 354. The cam 352 is located in the housing part of the combined housing and shaft support 349, which housing is provided with a cover plate 355 that has a radial slot 355a as will later more fully appear. The cover 355 also constitutes a base plate for the bottom curl slide 357 which is movable along a radius of the forming turret between gibs 356. The slide 357 is bored and provided with radial bearings 358 and a thrust bearing 360 in which a drive shaft 359 is journaled. 361 indicates a bearing cap and 362 an adjusting split nut on shaft 359.

363 is a bearing bracket in which is journaled the hollow bearing sleeve 365a of a pulley 365. The sleeve is held against longitudinal movement 75 in bearing bracket 363 by the pulley 365 and a

locking collar 364 secured on the bearing sleeve 365^a. A motor 368 drives the pulley 365 via a belt 366 and pulley 367^a on the shaft 367 of the motor 368. The shaft 359 is slidably keyed to pulley sleeve 365^a and pulley 365. Secured to the slide 357 is a stud which carries a cam roller 371 to run in groove 354 and a roller spacer 369 that operates in the slot 355^a. Secured to an end of the shaft 359 and locked by set screws 373 is a curl roller head 372 which has radial bores 374 in which are located a set of bottom curl rollers 375. The head 372 has a recess with an annular groove 374^a and the rollers 375 have annular grooves 375^a which line up with the groove 374^a.

Mounted slidably on pilot rods 392 secured in the slide 357, is a bottom curl clamp 376 which is electrically heated by a heater 377. The clamp 376 has a nose 376^a to fit over the cup body on the adjacent former and a shoulder 376^b against which the head 372 may engage when the head is advanced by the action of the cam 352.

383 is the bottom ejector lifting cam link which operates in a slideways 349^a and has a stud 378 carrying a cam roller 279 that operates in cam groove 353. Slidably mounted in a bearing bracket 389 is a slide 381 that is connected with the link 383 by a connecting bracket 382. The slide 381 has a beveled end 381^a to ride under a roller 387 on a stud 386 that is carried by each rod 205. Each rod 205 also has a latching finger 388 which cooperates with a latch 384 carried in a portion of the turret shaft bracket 183 and pressed outward, by a spring 385, against the cam track 207.

Compression springs are located on the rods 392 and a safety spring 398 is located on shaft 359.

397 is a motor base on which the motor 368 is mounted and 395 is a base on which the motor 418 for the bottom expander is mounted. The bases 397 and 395 are in one casting that is secured to the bottom expander base 398.

Carried on a slide 398 that is mounted on the base 396 are shaft bearings 399 in which a bottom expander tubular shaft 401 is journalled. The shaft 401 has a bottom expander head 403 on one end of the shaft and a tension spring guide nut 403 on the other end, which nut engages a thrust bearing 399^a at one side of the rear bearing 399 while a split nut 402 on shaft 401 engages the other side of said thrust bearing to hold shaft 401 against endwise movement in its bearings 399.

Slidably longitudinally in shaft 401 is a bottom expander slide block operating shaft 406 on one end of which, and within the head 403 is a conical nose 409. Longitudinal movement of shaft 406 in shaft 401 is limited by a pin and slot connection 407 between the shafts. Mounted between nut 403 and a tension spring guide washer 405 on shaft 406 is a tension spring 404. The washer 405 carries a ball thrust bearing 411 between which and a radial bearing 414 in a trunnion member 413 is a connecting sleeve 411^a. A slide block operating shaft adjusting nut 412 is threaded on the rear end of shaft 406 and abuts the radial bearing 414 (Fig. 44). The trunnion studs 415 of the member 413 ride in trunnion blocks 434 in the fork of a bell crank lever 433 that is pivoted at 432^a to a bracket 432 mounted on the base 396. A nose safety spring 419 is mounted on the shaft 406 between the washer 405 and a split nut 403. A split pulley 415 is secured to shaft 401 and is connected to a pulley 416 on the shaft of a motor 418 by a belt 417. The bearing 399 has laterally extended pilot rod bearings 419

in which pilot rods 420 are mounted. Slidable along the rods 420 is a clamp 421 that is adapted to slide along the rods 420 against springs 444 on the rods. The clamp 421 is provided with an electric heater 422 as indicated in Figs. 43 and 44. The clamp 421 is tubular and shaped to fit over the cup body on the adjacent conical former 191. Mounted in the expander head 409 is a roller operating slide block 423 that has a bearing lug 428 (Figs. 44, 52 to 54) and a beveled nose 427. The block 423 is held in place in the head 409 by retaining plates 425 and 443 and is normally held with the lug 428 in axial alignment with shaft 406 by springs 424. An adjustable stop 426 is provided in the plate 425 to limit the radial movement of the block 423. Rotatably mounted on the lug 428 through the medium of a ball bearing 431 is an expander roller 429 which has a bottom rolling portion 430 of the required shape. The roller 429 has a flange 429^a to engage a shoulder 421^a in the clamp 421. By virtue of this construction when lever 433 is rocked the slide 398 will be first moved from right to left in Fig. 44 against stop 442, at which time clamp 421 will have been placed over the end of the cup body and bottom assembly. Further movement of lever 433 in the same direction causes shaft 406 to advance until nose 409 forces block 423 radially outward to move lug 428 off center and cause roller 429 to roll the bent over portion of the body blank tightly and smoothly against the inside of the cup bottom flange to complete the bottoming operation.

Lever 433 is operated by means of a rod 437 slidable in a vertical guide bracket 436 mounted on base 1 and coupled to a fork 438 which straddles shaft 30 and has a roller 439 to ride the groove of a suitable cam 440 having its hub 441 secured to the shaft 30 (Figs. 44, 45).

By referring now to Figs. 14, 56 to 65 inclusive, 40 72 and 73, the construction of the top ending turret and its proximate associated mechanisms will be clear. In those figures, 445 represents the turret shaft housing which is mounted in a well 452 in the base 1 and (Fig. 56) has radial and thrust bearings 447 and 448 respectively, for the shaft 450. The housing 445 is provided with end caps 446 that serve to, in part, retain the bearings in place. Mounted on the upper end of the shaft 45 is the hub 451 of a top ending turret 449 which 45 is secured to the hub by cap screws 449^a and turns in a recess 449^b in the base 1. Mounted on the lower end of the shaft 450 is a Geneva gear 453 which is driven by a Geneva cam 456 and roller 457 carried on a vertical cam shaft 455 that 50 is journalled in bearings 458 in a bracket 454 secured to the underside of the well 452. A cap 459 on the lower end of bracket 454 holds the lower bearing 458 in place. The cam shaft 455 has a worm gear 460 which meshes with a worm gear 461 on the front cam shaft 21.

Mounted 60° apart on the turret 449 are six top ending cones 462, each having removable anvil inserts 463 and whose upper ends have an annular cavity 464, and whose inner faces have annular grooves 464^a for purposes presently more fully understood.

The turret 449 has bearings 465 for cup ejector spindles 466. The spindles 466 have nuts 467 between which and the lower ends of the bearings 465 ejector springs 468 are located. To the upper end of each spindle 466 an ejector head 469 is secured by a screw 470. The spindle 466 and head 469 each have an air passage 471 which, as the cone 462 reaches the discharge station, 70 effects communication with the air port 583 of

a cam track 584 (Fig. 72). The port 583 is in communication with the compressed air system (later again referred to) so that when a cone 462 reaches the discharge station, after riding up the cam track 582, compressed air will blow out the finished cone and discharge it via a suitable duct or chute 589 that is carried by a chute holder 586 adjustably mounted on a bracket 584 attached to base 1 (Fig. 72) by means of a dovetail extension 587 of the holder that fits a dovetail slot 585 in the bracket 584. Adjusting screws 588 are provided on the holder 586 for raising and lowering the chute entrance of the holder to properly position it with regard to the cone insert 463.

As best shown in Fig. 59, 472 designates a top curl operating shaft bracket which is secured to the base 1 and projects through an aperture 13 in the base. Working up and down in the bracket 472 is a shaft 482 which, at its upper end carries a bracket 475. The bracket 475 has a tail piece 475^a to which is attached a pilot pin 473 that operates in a guide 474 parallel to shaft 482.

The bracket 475 has a top curl head 476, in which is mounted, for limited vertical movement, the shank 477^a of a top curl head 477. A coil spring 488 serves continuously to push the head 477 downwardly, the downward movement being limited by a head screw 487 that abuts the upper end of the curl head guide 476 and is screwed into the upper end of the shank 477^a. The head 477 has a chamber in which is located an electric heater 478 having terminals 489 to which an electric circuit can be connected, a top curl iron 479 being secured to the shank (Fig. 62). The iron 479 has teeth 494 which are slotted across, radially and are divided by an annular cup edge turning groove 494^a.

A clamp shaft 489 is connected to the head 477 by means of a pin and slot connection 491 so that shaft 489 will be free to move up and down a limited distance, a spring 492 serving to effect normal disengagement between the teeth 494 and the clamp 490 that is mounted on the lower end of the shaft 489 and has slots 493 to receive the inner parts of the teeth 494. By reference to Fig. 62 it will be seen that with a cup C in place in the cone 462, and guide 476 is lowered, clamp 490 will first enter the cup and wedge it to the anvil insert 463. Further downward movement of guide 476 causes the top curl iron 479 to come down on the top edge of the cup and curl it over into a bead and iron same. A suitable thermostatic switch 481 serves to control the heat generated by the heater 478.

In order to lower and raise the guide 476 and the parts carried by it, the shaft 482 is coupled to a roller fork 483, whose roller 484 operates in the cam 485 on the cam shaft 21 which cam shaft has a fork guide 486.

Referring now to Figs. 1, 1^A and 64 it will be seen that 495 indicates a top beader bracket of somewhat similar form to that of bracket 475 and carrying at one end a spindle guide 495^a for beader spindle 502. The bracket 495 is mounted on the upper end of an operating shaft 497 that is movable up and down in a guide bracket 498 (Fig. 1^A) similar to the bracket 472. The bracket 495 has a pilot pin 501 that works in a guide similar to the guide 474. The shaft 497 is joined to a roller fork 498 whose roller 499 operates in the groove of a cam 500 on shaft 21 (see Fig. 55).

502 designates the beader spindle which works up and down in bearings in the guide 495^a, the downward movement being limited by adjusting

nuts 502^a and the upward movement being against the force of a spring 513^a within the guide 495^a. 513 is a spring which bears against the guide 495^a and a beader cover 512 held on the spindle 502 by the spindle nose 503 whose nose 509 is screwed into the lower end of the spindle (Fig. 64). The cover 512 is recessed as at 512^a for the nose 503 and at 503^b for the segmented beader, the segments 504 of which have guide pins 506 which work in radial slots 508 in a clamp and pin guide 507. The guide 507 is secured to the threaded stem 510 of the nose 503, by nuts 511. An oil duct 514 in the guide 495^a enables the bearing 495^b to be lubricated. The segments 504 are held together by a coil spring 505 located in an annular groove 504^a. The set of segments 504 have an annular flange 504^b which, when the segments are expanded with the clamp in operative position, will force a part of the cup wall into the groove 464^a and thereby form a bead on the cup.

In operation as the bracket 495 is lowered clamp 507 will enter the cup and wedge it tightly to the anvil insert 463, with the flange 504^b in line with groove 464^a and will bring cover 512 down on the curled over edge of the cup. Further downward movement of the bracket 495 causes nose 503 to spread segments 504 outwardly and thus form the bead on the cup.

Referring now to Figs. 66 to 70 inclusive it will be seen that the mechanism for applying glue to the body blanks comprises a glue wheel drive base 515 on which is mounted a seam glue wheel slide base 516. Removably mounted on a bracket 519 that is secured to the base 515 is glue box 518.

Mounted on the cam shaft 21 is a worm drive gear 520 that meshes with a driven gear 521 on a countershaft 522 that is journaled in a bearing 517^a on the gear housing 517 that is mounted on the underside of the top of base part 1. The shaft 522, within the housing 517 carries a drive gear 523 that meshes with a driven gear 524 on a driven shaft 525 (Fig. 67).

The shaft 525 is journaled in bearings 526, 527 formed integrally with the hollow base 515. At its upper end the shaft 525 carries a beveled drive gear 558 which meshes with a driven gear 559 on a bottom glue wheel shaft 557 that is journaled in bearings 557^a, 557^b in the glue wheel slide base 516. Within the base 515 the shaft 525 carries a bevel gear 528 that meshes with a pinion 529 on the seam glue wheel shaft 530 that is journaled in a fixed bearing 531^a and a removable bearing 531 on the glue box 518. A glue wheel 532 is mounted on the shaft 530 and projects through the glue box cover 534 and a glue wheel scraper 535 mounted on the cover 534. Packing washers 533 are provided to protect the shaft and bearings from contact with the glue in the box 518 (see Fig. 68). The glue box 518 has a dove-tail slidable connection 519^a with the bracket 519 and is held in position by means of a set screw 536 (Fig. 67).

Suitably secured to the base 516 are slide guides 537 between which a glue wheel slide 538 is mounted (Figs. 67, 68). An arm 539 is formed with a slide 538 and has a stud 540 on which a rubber glue applying roller 543 is mounted and is held in place on the stud by locking plate 541. Movement of the slide 538 in one direction is arrested by an adjustable bumper 542.

544 is the bottom glue wheel applying shaft which is journaled in bearings 544^a attached to the base 516 (Figs. 67, 68).

Torsion springs 546 serve to move the shaft 544 in its backward or return movement while movement forward or advance motion is given to the shaft via pinion 547 and a segment gear 548, spring collars 545 being provided on shaft 544 to which an end of a spring is attached, the other end of the spring being suitably anchored.

The segmental gear 548 is pivoted on a stud 549 and carries a stud 550 on which a cam roller 551 is mounted so as to engage the bottom glue wheel operating cam 563. The cam 563 is mounted on the shaft 525.

A glue applying roller 554 is mounted on a stud 553 on an arm 552 that is carried by shaft 544. The roller 554 normally rides in contact with a glue box wheel 555 that is carried on a shaft 557. The shaft 557 is journalled in a fixed bearing 557^a and a removable bearing 557^b hereinbefore mentioned. The glue box 556 has a cover 560 (Fig. 66) and a cover adjusting screw 561, and latch 562 is provided as shown.

On the shaft 525 and located within the base 515 is a gear 564 which meshes with cam gear 566 that is journalled on a stud 565 and carries an operating cam 567. The gear 566 and cam 567 may be formed integrally or separately and suitably secured together to turn as one (see Fig. 68).

568 is a cam roller arm which is secured to a shaft 571 that is journalled in a suitable bearing 572 in the base 515. The shaft 571 projects up into the base 516 where it carries a torsion spring 574 one end of which is anchored to a stud 575 on the base 515 and the other end is anchored to a stud 575^a on an arm 573. The arm 568 has a stud 569 on which the seam glue wheel operating cam roller 576 is journalled.

The arm 573 carries a trunion block 576 on a pin 577 and to which a glue wheel slide connecting link 578 is pivoted. The glue wheel slide 588 has lugs 589 secured to it. The connecting link 578 connects to the lugs 579 via a pin 580, a compression spring 581 being provided for the usual purposes as indicated in Fig. 66.

The gluing mechanism just described is timed so that the wheel 554 will be swung down onto a cup body blank to apply glue for the bottom while the blank is carried around over the table top 142 by the blank conveyor turret; the roller 543 is operated to apply the seam glue after the blank conveyor turret has stopped. As the construction and operation of the glue applying mechanism is well known, see Letters Patent No. 1,766,420 issued June 24, 1930, and its detailed operation is fully disclosed in said patent and no claim to the glue applying mechanism per se is made herein, further description of the mechanism and its operation is thought to be unnecessary in this specification.

After the cup body has been formed and the bottom has been fully applied to the body portion of the cup, the cup is blown off the mandrel into a cup transfer device which delivers the cup into a top ending cone on the top ending turret 449. The transfer device is best disclosed in Fig. 73 by reference to which it will be seen that a bracket 590 is secured to the base 1 and has a dove-tail slot 591 to receive the dove-tail guide portion 592^a of a chute supporting arm 592. The arm 592 has an integral horizontal ring 595 to which the lower ends of guide wires are secured. The upper ends of the guide wires 595 are secured to a vertical ring 594. The ring 594 is secured to the upper end of arm 592 by cap screws 594^a. Adjusting screws 596 enable the

ring 593 to be properly spaced above the top ending cone 462, 463.

Lubrication is provided by a pump operated oil circulating system, schematically illustrated in Fig. 74, utilizing the bottom section 14 as an oil sump 14^a. Oil is drawn from the sump via a strainer 599 and outlet pipe 598 to a suitable oil pump (not shown) and returned under pressure via an inlet pipe 597, connecting pipe 601, 10 riser 600 to header pipes 602, 603, 604 and 605 from whence the oil is taken under pressure by small distributing ducts 606 to the various bearings located within the base that require lubrication.

15 Compressed air for operating the cup blow-offs and transfer devices is obtained from an outside source (not shown) and is controlled by a single push type valve 613 mounted on the top of base 1 and operated by the shaft 482. When that shaft goes down valve 613 is opened and when shaft 482 goes up valve 613 closes automatically. Air enters the valve via a pipe 614 and is distributed to the forming turret blow-off nozzle 616 and blow-off air connection bracket 625, and 20 the top ending turret air duct 583 via a duct 615 and branches 615^a thereof (Figs. 1^a, 72 and 73).

The bracket 625 is suitably secured to the base 1 and has an air passage 626 which communicates with a similar passage through a blow-off air 25 connection pad 629 via a bracket tube 628. The pad 629 is secured to the top of the bracket by screws 630 and dowels 628 (Fig. 75).

617 is a chute for delivering waste from the body blanking mechanism. The cut-off waste 35 portions are dropped into the chute and are blown out by a compressed air nozzle 618 to which at predetermined intervals compressed air is delivered from a control valve 619 via a duct 620 (Fig. 4^a) that is operated by a cam 621 on 40 shaft 114. Compressed air is delivered to valve 619 from the outside source before referred to by suitable piping 622. Suction for the picker is controlled by a valve 623 operated by a cam 624, the valve being connected to the duct 131 and to a 45 pipe 625 from a suitable source of suction (as for example a vacuum pump) not shown.

Attention is called to the fact that in forming the cup bottom the flange of the bottom is corrugated inwardly, i. e., toward the axis of the 50 bottom so that the outer surface of the bottom's flange is smooth, i. e., forms a continuous cylindrical face. When the bottom is pushed out of the former into the overhanging end of the body prior to the action of the bottom curler (Fig. 37) 55 a substantially full contact of the outer surface of the flange and the inner surface of the cup body is obtained. After the end of the cup body has been curled over the bottom flange and the expander 429 (Fig. 44) is brought into action, the 60 folding or flattening of the corrugations of the bottom's flange all take place at the innerside of the cup bottom and no unevenness is therefore apparent on the outside of the cup which remains perfectly smooth and gives to the cup the appearance of a one-piece cup.

What we claim is:

1. In a machine of the class described, a turret shaft bracket, a turret shaft journalled in said bracket, a rotatable turret carried by said shaft and including a chambered body with at least one chambered conical former attached thereto with its axis disposed in a radial direction, said former having a cup bottom receiving recessed outer end and having spindle bearing portions, a 70 bottom ejector spindle having an ejector head 75

at one end located in the recess of said outer end, said spindle having its other end projected into the chamber of said chambered body, an ejector operating shoe radially slidably mounted in the chamber of said chambered body, means continuously urging said spindle into engagement with said shoe, a bottom ejector lift rod mounted in bearings in said bracket and operatively connected with said shoe, a latching finger on said rod, a yieldable latch on said bracket for cooperating with said finger to hold said rod elevated and said spindle and its ejector head locked in their ejecting position at times, and means to raise said rod to the latched position.

2. In a machine of the class described, a turret shaft bracket, a turret shaft journaled in said bracket, a rotatable turret carried by said shaft and including a chambered body with at least one chambered conical former attached thereto with its axis disposed in a radial direction, said former having a cup bottom receiving recessed outer end and having spindle bearing portions, a bottom ejector spindle having an ejector head at one end located in the recess of said outer end, said spindle having its other end projected into the chamber of said chambered body, an ejector operating shoe radially slidably mounted in the chamber of said chambered body, means continuously urging said spindle into engagement with said shoe, a bottom ejector lift rod mounted in bearings in said bracket and operatively connected with said shoe, a latching finger on said rod, a yieldable latch on said bracket for cooperating with said finger to hold said rod elevated and said spindle and its ejector head locked in their ejecting position at times, and means to raise said rod to the latched position, said last named means including an ejector lift slide having a beveled end, a roller on said rod, and a rotating cam operatively connected with said slide for projecting said slide under said roller to lift said rod to a latched position.

3. In a machine of the class described, a turret shaft bracket, a turret shaft journaled in said bracket, a rotatable turret carried by said shaft and including a chambered body with at least one chambered conical former attached thereto with its axis disposed in a radial direction, said former having a cup bottom receiving recessed outer end and having spindle bearing portions, a bottom ejector spindle having an ejector head at one end located in the recess of said outer end, said spindle having its other end projected into the chamber of said chambered body, an ejector operating shoe radially slidably mounted in the chamber of said chambered body, means continuously urging said spindle into engagement with said shoe, a bottom ejector lift rod mounted in bearings in said bracket and operatively connected with said shoe, a latching finger on said rod, a yieldable latch on said bracket for cooperating with said finger to hold said rod elevated and said spindle and its ejector head locked in their ejecting position at times, and means to raise said rod to the latched position, said last named means including an ejector lift slide having a beveled end, a roller on said rod, and a rotating cam operatively connected with said slide for projecting said slide under said roller to lift said rod to a latched position, and means to turn said turret shaft to cause said finger to ride off said latch and release said rod.

4. In a machine of the class described, a support, a turret shaft rotatably mounted in said support, a turret body carried by said shaft and

having a conical former thereon the axis of which former lies radially to said shaft, said former having a recessed end to hold a flanged cup bottom, a bottom ejector spindle mounted in said former and having a head located in said recess, means continuously tending to hold said spindle and head retracted, a shoe radially slidably mounted in said turret body and engaging said spindle, means to move said shoe to advance said spindle, said last named means including a reciprocating rod operatively connected with said shoe, a stationary track on which said rod rides during rotation of the turret, a bottom curl mechanism, means to arrest said turret when said conical former is lined up with said bottom curl mechanism, a latch device carried by said support, a latch finger carried by said rod, and means controlled by said bottom curl mechanism for raising said rod to latch the same and cause said rod to effect the ejection of the cup bottom from said recess.

5. In a machine of the class described, wherein a cup forming turret body is rotatably mounted on a vertical axis and carries a set of radially disposed formers, said machine having a cup bottom receiving station, a body blank applying station, a turret locking station, a bottom ejecting and curl station, a bottom expander station, a top ending station and a discharge station in the order mentioned, the invention which comprises conical formers having recessed ends to receive cup bottoms at the bottom receiving station, and having means on the formers and the turret body for ejecting cup bottoms from said recessed ends at the bottom ejecting and curl station, said means including for each conical former an ejector spindle having a head located in the spindle end recess, an ejector operating shoe carried by the turret head to engage said spindle, yieldable means holding said ejector head in a non-ejecting position, means including a lifting rod operatively connected with said shoe, which rod when elevated serves to move said shoe to effect ejection of the cup bottom from said recessed end, means to latch said rod in its elevated position at the bottom ejecting and curl station, and means at said bottom ejecting and curl station for first raising said rod to its latched position to eject the cup bottom and then curling the edge of a cup body, that had been previously applied to the conical former, over the cup bottom flange, and means to hold said rod elevated after passing the bottom curl station until the bottom expander station shall have been passed.

6. In a machine of the class described, wherein a cup forming turret body is rotatably mounted on a vertical axis and carries a set of radially disposed formers, said machine having a cup bottom receiving station, a body blank applying station, a turret locking station, a bottom ejecting and curl station, a bottom expander station, a top ending station and a discharge station in the order mentioned, the invention which comprises conical formers having recessed ends to receive cup bottoms at the bottom receiving station, and having means on the formers and the turret body for ejecting cup bottoms from said recessed ends at the bottom ejecting and curl station, said means including for each conical former an ejector spindle having a head located in the spindle end recess, an ejector operating shoe carried by the turret head to engage said spindle, yieldable means holding said ejector head in a non-ejecting position, means including a lifting rod operatively connected with said shoe, which

rod when elevated serves to move said shoe to effect ejection of the cup bottom from said recessed end, means to latch said rod in its elevated position at the bottom ejecting and curl station, and means at said bottom ejecting and curl station for first raising said rod to its latched position to eject the cup bottom and then curling the edge of a cup body, that had been previously applied to the conical former, over the cup bottom flange, and means to hold said rod elevated after passing the bottom curl station until the bottom expander station shall have been passed, said last named means comprising a stationary cam track operatively engaged by said rod.

7. In a machine of the class described, wherein in a cup forming turret body is rotatably mounted on a vertical axis and carries a set of radially disposed formers, said machine having a cup bottom receiving station, a body blank applying station, a turret locking station, a bottom ejecting and curl station, a bottom expander station, a top ending station and a discharge station in the order mentioned, the invention which comprises conical formers having recessed ends to receive cup bottoms at the bottom receiving station, and having means on the formers and the turret body for ejecting cup bottoms from said recessed ends at the bottom ejecting and curl station, said means including for each conical former an ejector spindle having a head located in the spindle end recess, an ejector operating shoe carried by the turret head to engage said spindle, yieldable means holding said ejector head in a non-ejecting position, means including a lifting rod operatively connected with said shoe, which rod when elevated serves to move said shoe to effect ejection of the cup bottom from said recessed end, means to latch said rod in its elevated position at the bottom ejecting and curl station, and means at said bottom ejecting and curl station for first raising said rod to its latched position to eject the cup bottom and then curling the edge of a cup body, that had been previously applied to the conical former, over the cup bottom flange, and means to hold said rod elevated after passing the bottom curl station until the bottom expander station shall have been passed, and means at said bottom expander station for expanding the curled over portion of the cup body onto the cup bottom flange.

8. In a machine of the class described, wherein in a cup forming turret body is rotatably mounted on a vertical axis and carries a set of radially disposed formers, said machine having a cup bottom receiving station, a body blank applying station, a turret locking station, a bottom ejecting and curl station, a bottom expander station, a top ending station and a discharge station in the order mentioned, the invention which comprises conical formers having recessed ends to receive cup bottoms at the bottom receiving station, and having means on the formers and the turret body for ejecting cup bottoms from said recessed ends at the bottom ejecting

and curl station, said means including for each conical former an ejector spindle having a head located in the spindle end recess, an ejector operating shoe carried by the turret head to engage said spindle, yieldable means holding said ejector head in a non-ejecting position, means including a lifting rod operatively connected with said shoe, which rod when elevated serves to move said shoe to effect ejection of the cup bottom from said recessed end, means to latch said rod in its elevated position at the bottom ejecting and curl station, and means at said bottom ejecting and curl station for first raising said rod to its latched position to eject the cup bottom and then curling the edge of a cup body, that had been previously applied to the conical former, over the cup bottom flange, and means to hold said rod elevated after passing the bottom curl station until the bottom expander station shall have been passed, said rod raising and curling means including a bottom curl cam housing and shaft support, a cam shaft journalled in said support, a cam in said housing and mounted on said cam shaft, a slide mounted on said housing for movement toward and from an aligned former on said turret, means operatively connecting said slide with said cam, a drive shaft journalled in bearings in said slide, means for turning said drive shaft, a roller head on said drive shaft, body blank curling rollers on said roller head, a clamp yieldingly supported on said slide for embracing the cup body at its bottom end and having a passage for said roller head, and means operated by said cam for raising said rod to its bottom ejecting position and in latching engagement with said latch prior to the advancement of said slide.

PAUL E. WIXON.
CLARENCE E. CHAPMAN.
